UNITED STATES PATENT OFFICE.

MONTGOMERY C. MEIGS, OF WASHINGTON, DISTRICT OF COLUMBIA.

FILE-CASE.

SPECIFICATION forming part of Letters Patent No. 451,599, dated May 5, 1891.

Application filed July 25, 1885. Serial No. 172,669. (No model.)

To all whom it may concern:

Be it known that I, MONTGOMERY C. MEIGS, a citizen of the United States, residing at Washington, in the District of Columbia, have 5 invented certain new and useful Improvements in File-Cases; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention relates to file-cases for bills, 15 papers, and other documents; and it consists in the novel manner of constructing the same, hereinafter fully described and claimed, by which the cost of constructing a file-case is very greatly reduced, and by which the papers contained within it are preserved from destruction by fire.

Prior to this invention file-cases have been constructed of wood and metal in the form of pigeon-holes, so that the papers placed within 25 them have been preserved from dust and have been kept in an easily-accessible form for reference; but none of the methods of forming the pigeon-holes have afforded any effectual protection against fire which might be communicated to their contents by any adjacent burning material. File-cases have been formed in the interior of fire-proof safes and 30 vaults, which in some cases form a part of the outer walls of the file-case; but when constructed in this manner the cost is very great and there is nothing to prevent the spread of fire from one pigeon-hole to another within 35 the limit of the outer fire-proof inclosing walls.

40 In carrying out my invention I construct the pigeon-holes in the form of rectangular boxes of terra-cotta, pottery-clay, porcelain clay, or brick or tile clay. These boxes may be formed singly or in pairs, or otherwise, as 45 desired, by forcing the material through a suitable die and afterward firing it in the usual manner adopted for manufacturing articles in terra-cotta and clay. Each of the terra-cotta boxes thus formed and containing 50 one or more pigeon-holes is provided with suitable guides upon its exterior surface, so that a series of the boxes when built together

will form a second series of pigeon-holes between their next adjacent exterior surfaces. The rear of the pigeon-holes may be stopped 55 up with plates of terra-cotta or clay; but when the boxes are built against a wall I generally prefer to line the surface of the wall with plates of terra-cotta or clay and build the boxes up against it in preference to stopping up the 60 rear end of each pigeon-hole with a separate plate. I use doors for closing the front ends of the pigeon-holes. These doors are made of terra-cotta or clay and provided with suitable lugs or hinges for holding them in place, 65 which lugs or hinges engage with other lugs or holes near the front end of the boxes. The doors may be firmly secured in close contact with the box, when required, by means of any of the well-known locking devices or appliances commonly in use. These latter arrangements are, however, rarely necessary, except in the case of records to be very seldom consulted, examined, or handled.

I will now proceed to describe my invention 75 with reference to the accompanying drawings, in which—

Figure 1 is a perspective view of a recess in the interior of a building, partly filled with a file-case consisting of variously-modified forms 80 of boxes. Fig. 2 is a perspective view of a simple form of box. Fig. 3 is a modification of the same. Fig. 4 is a side view of one of the doors.

Similar letters of reference indicate corresponding parts in all the figures.

A represents a simple form of terra-cotta box, rectangular in shape and having beveled corners which form guides a, so that a series of boxes A can be built together, as shown in 90 Fig. 1, and form a second series of pigeon-holes between their next adjacent outside surfaces.

A' is a modification of the same form of box. This has two pigeon-holes in it and is 95 provided with guides a, similar to those on box A.

B is a simple form of box, which may be used to fill in corners, or it may be used separately, or a row of them may be placed on a 100 shelf or in other situations where guides are not necessary.

B' is a modification of the rectangular box A. This box B' is also made of terra-cotta or

clay, but has its guides formed with it in the shape of strips or lugs *b* upon the bottom side. It is obvious that the said strips *b* might have also been formed upon the top as well as upon

5 the bottom side of the box, the object being to guide the boxes so that they form a second series of pigeon-holes when built together.

*B*² is a modification of the box *B*' and has two pigeon-holes in it.

10 *C* are back plates of terra-cotta or clay. They close up the rear ends of the pigeon-holes and prevent any fire occurring in the wall of the building from extending to the papers in the file-case.

15 *D* and *D'* are differently-shaped plates for closing in the spaces between the boxes at the top and bottom of the file-case. These plates are also made of terra-cotta or clay.

E are doors formed of terra-cotta or clay 20 for closing the front ends of the pigeon-holes. These doors are provided with suitable lugs *e* or hinges for holding them in place, and may have knobs or handles formed upon them for convenience in use.

25 Any kind of mortar or cement which will withstand fire and heat may be used to join the boxes together; or the boxes may be placed together without any cement between them.

30 Having thus described my invention, what I claim as new, and desire to secure by Letters Patent, is—

35 1. A file-case consisting of a series of rectangular boxes of fire-proof material provided with corner-guides and arranged in quincunx order, so that a second series of boxes is formed between the next adjacent outside surfaces of the said boxes when built together, substantially as shown and described.

40 2. A fire-proof file-case consisting of a series of rectangular boxes of terra-cotta, each containing one or more pigeon-holes and provided with guides and arranged in quincunx order, so that a second series of pigeon-holes is 45 formed between the next adjacent outside surfaces of the said boxes when built together, in combination with the back plates and doors of the same material, substantially as described and shown.

3. In a fire-proof file-case, the rectangular box *A*, formed of terra-cotta and provided with guides *a*, substantially as and for the purpose set forth. 50

4. In a fire-proof file-case, the combination of a series of rectangular boxes *A*, formed of terra-cotta and provided with the guides *a*, with the plates *D'*, the back plates *C*, and the doors, substantially as and for the purpose set forth. 55

5. A file-case consisting of a series of rectangular boxes of fire-proof material arranged in quincunx order, so that additional file-boxes are formed between the said rectangular boxes, substantially as and for the purposes set forth. 60

65 6. A file-case consisting of a series of rectangular boxes of fire-proof material arranged with spaces between them, in combination with fire-proof plates or surfaces inclosing said spaces on the sides not occupied by the said boxes, whereby additional boxes are formed between the said rectangular boxes, substantially as and for the purpose set forth. 70

7. A file-case consisting of a series of open-ended boxes of fire-proof material built against a wall which closes the rear ends of the boxes, thereby forming a series of file-boxes, substantially as and for the purpose set forth. 75

8. A file-case consisting of a series of open-ended boxes of fire-proof material, in combination with a wall lined with fire-proof plates, against which the boxes are built, thereby forming a series of file-boxes, substantially as and for the purpose set forth. 80

9. A file-case consisting of a series of open-ended boxes of fire-proof material built end-wise against a wall in quincunx order, thereby forming file-boxes both of the open-ended boxes and of the intermediate spaces, substantially as and for the purpose set forth. 85

90 In testimony whereof I affix my signature in presence of two witnesses.

M. C. MEIGS.
